CLAIM

The ornamental design for a blender base, as shown and described.

DESCRIPTION

FIG. 1 is a side perspective view of a blender base configured for use with a container;

FIG. 2 is a front view of the blender base;

FIG. 3 is a back view of the blender base;

FIG. 4 is a left view of the blender base;

FIG. 5 is a right view of the blender base;

FIG. 6 is a top view of the blender base; and,

FIG. 7 is a bottom view of the blender base.

The broken lines defining a container depict environmental subject matter that forms no part of the claimed design.
